UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Application filed July 12, 1923. Serial No. 651,151.

This particular invention relates to what is generally known in the art as the push down or vertical plane type of uncoupling device and comprises two levers operatively connected having their adjacent ends pivotally mounted on the same fulcrum. Such devices are operated either by hand or foot. (The particular advantage of this construction resides in the manner in which the 10 levers are pivoted upon the fulcrum.) In levers of this general type the connection between the levers must allow the pin lifting lever to move freely laterally to accommodate the longitudinal movement of the 15 coupler in draft and in buffing.

The manner of operatively mounting the pin lifting lever upon the operating lever in accordance with this invention permits it to move or swing laterally to accommodate the movements of the coupler in buff and draft and the manner of mounting the operating lever upon the fulcrum prevents or restricts its moving or swinging laterally in a horizontal plane, so that the lateral 20 or pivotal movement of the pin lifting lever cannot be transmitted to the operating lever. The manner of mounting the pin lifting lever upon the operating lever prevents it from tipping and binding, thereby 25 causing friction in the device.

The impact of coupling causes sudden longitudinal movement of the coupler, which movement is transmitted to the adjacent end of the pin lifting lever and would be transmitted to the operating lever unless that lever is prevented from moving laterally. Switchmen frequently ride a moving car 30 while coupling it and at the same time signal the engineer. In such an act he usually holds on the grab iron with his left hand and signals the engineer with his right hand while his left foot is on the sill step and his right foot is on the operating lever. While 35 in such a position a sudden movement of the operating lever has a tendency to, and frequently does, throw him from the car. One of the objects, therefore, is to provide a device which is safe for the switchman to operate.

50 The return bend and the extended portion therefrom provides two bearings which are provided in parts of the same metallic bar, therefore, act in unison to increase the bearing area of the operating lever upon the fulcrum, prevent or restrict it from moving

or swinging laterally and prevent it from tipping from a vertical plane.

Good practice requires that the handle end of the operating lever be positioned slightly in front of the vertical plane of the 60 face of the end sill and below the push pole pocket. This is a generally recognized location of this handle, therefore, switchmen can reach it quickly even in the darkness. It is advantageous, therefore, to not permit 65 the lever to move laterally, and especially advantageous not to allow the sudden or jerky movement of the pin lifting lever to be transmitted to the operating lever.

Means are provided to restrict the movement of the lever in a vertical plane which is a requirement of the Interstate Commerce Commission safety appliance acts.

In the drawings:

Fig. 1 is a perspective view of a car with 75 my invention applied thereon.

Fig. 2 is an enlarged detail of the fulcrum.

Fig. 3 is a plan view of the fulcrum end 80 of the operating lever.

Fig. 4 is an elevation of the fulcrum end of the operating lever.

Fig. 5 is a plan view of the fulcrum end of the pin lifting lever.

Fig. 6 is an elevation of the pin lifting 85 lever.

The usual parts of the car are shown, such as the end sill 1; the push pole pocket 2; the coupler 3; the lock lifter 4; the striking casting 5; the carry iron 6. 90

The operating lever 7 is mounted on fulcrum 8 and the pin lifting lever 9 is mounted on the operating lever 7. This pin lifting lever is operatively connected to the lock lifter 4 of the coupler 3. The operating 95 lever 7 is extended toward the side of the car to any convenient location so that it can be operated by hand or foot. A downward pressure on the end 10 of the operating lever 7 raises the lock lifter 4 of the coupler. The 100 lock is thus raised from behind the tail of the knuckle which permits the knuckle to swing outwardly and uncouple the cars; in fact, the raising of the lock automatically throws the knuckle. This, however, is within 105 the head of the coupler and has nothing to do with this invention.

The operating lever 7 has a rebent portion 11 which is extended to form portion 12. This portion 12, as well as the body 7 of the 110

lever, has perforations 13 and 14 which engage journal 15 of the fulcrum 8 to form two bearings of the lever on the fulcrum. The pin lifting lever 9 is provided with an 5 elongated eye 16 which engages rebent portion 11 of the operating lever and forms an operative connection between the two levers. The operating lever 7 is retained upon the fulcrum 8 by bolt 17.

10 The operating lever 7 is provided with a lug or stop 18 which engages walls 19 and 20 of the fulcrum 8 to restrict its movement in a vertical plane. Restricting this movement in the operating lever also restricts this 15 movement in the pin lifting lever.

In the operating lever the horizontal distance between portion 12 and the main portion 7 is only slightly larger than portion 21 of the pin lifting lever so that the pin lifting 20 lever is held in substantially a vertical position, thus preventing its tipping and wabbling.

The end of the fulcrum lever 9 is provided with an elongated eye 16 so that it must be 25 mounted upon the operating lever 7 before lever 7 is mounted upon the fulcrum, and furthermore, the connection between the two levers does not require the use of any bolts, nuts, cotters, etc., which may be lost and thus 30 disconnect the two levers.

I claim:

1. An uncoupling device for car couplers comprising a fulcrum, an operating lever having two bearings upon said fulcrum, and 35 a pin lifting lever operatively mounted upon said operating lever between the fulcrum and the coupler.

2. An uncoupling device for car couplers comprising a fulcrum, an operating lever 40 having a return bend at its fulcrum end extended to provide two bearings upon said fulcrum, and a pin lifting lever operatively mounted upon said operating lever between the fulcrum and the coupler.

45 3. An uncoupling device for car couplers comprising a fulcrum, an operating lever having its fulcrum end bifurcated to provide two bearings upon said fulcrum, and a pin lifting lever operatively mounted upon 50 said operating lever between the fulcrum and the couplers.

4. An uncoupling device for car couplers

comprising a fulcrum, an operating lever having a return bend at its fulcrum end extended to provide two bearings upon said 55 fulcrum, and a pin lifting lever having one end operatively mounted on said bend and the other end operatively connected to the coupler.

5. An uncoupling device for car couplers 60 comprising a fulcrum, an operating lever formed of a rectangular metallic bar having a return bend at its fulcrum end extended to provide two bearings upon said fulcrum, and a pin lifting lever having a rectangular 65 aperture at one end to engage said bend, the other end of said pin lifting lever operatively connected to said coupler.

6. An uncoupling device for car couplers 70 comprising a fulcrum, an operating lever having a return bend at its fulcrum end extended to provide two bearings upon said fulcrum, said extended portion continued to form a stop for engagement with said fulcrum, and a pin lifting lever operatively 75 mounted upon said operating lever.

7. In an uncoupling device for car couplers comprising an operating lever provided with an aperture, said lever rebent to form a portion provided with an aperture, 80 a fulcrum mounted upon the car passing through said apertures having a rotative connection therewith, and a pin lifting lever operatively mounted on said operating lever.

8. An uncoupling device for car couplers 85 comprising a fulcrum, an operating lever having a return bend at its fulcrum end extended to provide a double engagement with said fulcrum so as to restrict the lateral swing of said lever, and a pin lifting lever 90 mounted on said bend so as to hold it in substantially vertical position.

9. An uncoupling device for car couplers comprising a fulcrum, an operating lever having a return bend at its fulcrum end extended to provide a double engagement with 95 said fulcrum so as to restrict the lateral swing of said lever, and a pin lifting lever mounted on said bend so as to permit it to swing laterally to accommodate the movements of the coupler in service and so as to hold it in substantially vertical position.

GARTH G. GILPIN,
